UNITED STATES PATENT OFFICE.

WILLARD A. KITTS, JR., OF MOUNTAIN LAKES, NEW JERSEY, ASSIGNOR TO KITTS STEAM SPECIALTY CO., INC., OF OSWEGO, NEW YORK, A CORPORATION OF NEW YORK.

DAMPER-REGULATOR.

1,272,459.

Specification of Letters Patent. Patented July 16, 1918.

Application filed February 1, 1917. Serial No. 145,898.

To all whom it may concern:

Be it known that I, WILLARD A. KITTS, Jr., a citizen of the United States of America, and resident of Mountain Lakes, in the county of Morris, in the State of New Jersey, have invented new and useful Improvements in Damper-Regulators, of which the following, taken in connection with the accompanying drawings, is a full, clear, and exact description.

This invention relates to certain improvements in damper regulators as applied more particularly to steam boilers for automatically maintaining an approximately uniform predetermined steam pressure.

The main object of my present invention is to positively open and close one or more draft-controlling dampers of a steam boiler or battery through the medium of one or more hydraulic motors, preferably of the piston type, and to automatically control the operation of said motor or motors by the fluctuations of steam pressure in the boiler above or below a predetermined degree.

Other objects and uses relating to specific parts of the apparatus will be brought out in the following description.

In the drawings—

Figure 1 is a side elevation, partly in section, of an apparatus embodying the various features of my invention, the damper being shown diagrammatically in its normal or open position and by dotted lines in its closed position.

Fig. 2 is a transverse vertical sectional view taken on line 2—2, Fig. 1.

Fig. 3 is an enlarged sectional view through the pilot valve and its case.

The entire apparatus is adapted to be made up as a unitary article of manufacture to be easily and quickly installed in the boiler-room or other desired locality where it may be conveniently connected to the boiler and to the damper, and for this purpose comprises a main supporting frame or shelf —1— carrying a pair of hydraulic motors —2— and —3— consisting, in this instance, of coaxial cylinders —4— and —5— arranged end to end in spaced relation and on a diametrical line to one side of the diametrical line through lever —26— and hollow steam-receiving shell —28— and containing suitable pistons —6— and —7— which are connected by a cutout hollow rod

or stem —8—, as shown more clearly in Fig. 1.

The adjacent ends of the cylinders are preferably open to the atmosphere for reducing to a minimum the resistance to the movement of the pistons toward said ends, the opposite ends of the cylinders being closed by suitable caps —9— and —10— which are rigidly clamped to adjacent endheads —11— of the frame —1— and are provided with relatively small coaxial inlet —12— and —13— for connection, respectively, with a main supply pipe —14— and a branch supply pipe —15—.

The main supply pipe —14— may be connected to any available source of liquid supply under pressure, such for example as a water-distributing system for maintaining a more or less constant pressure in the cylinder —4— and upon the piston —6—, tending to force and to hold the latter at the extreme opposite end of its cylinder.

The branch pipe —15— leads from the main supply pipe —14— around the cylinders and is connected to the inlet —13— so as to direct the pressure against the corresponding piston —7—, tending to move the latter in a direction opposite to that which acts upon the piston —6—.

Connected in the branch pipe —15— is a valve case —16— containing what is commonly known as a pilot valve —17— which not only controls the flow of the motive fluid to the cylinder —5— for operating the corresponding piston —7—, but also controls the exhaust of the motive fluid from said cylinder when the corresponding piston —7— is returned to its normal position by the piston —6— through the medium of the connecting rod —8—, as will hereinafter be more fully described.

One section of the branch pipe —15— communicates with a relatively small opening in the bottom of the valve case —16—, while the other section communicates with a similarly small opening in one side of the valve case just above the bottom, which latter is provided with a valve seat, against which the lower end of the valve normally rests to control the passage of the motive fluid through the branch conduit —15—.

The valve case —16— is suitably secured in an opening in the bottom of an exhaust-receiving tray or cup —18—, which, in

turn, is rigidly secured to the upper portion of the main supporting frame or shelf —1— so as to surround the upper portion of the valve case.

- 5 The upper end of the valve case is closed by a screw cap —19— having a valve seat in its lower end for engagement by the upper end of the valve —17— when the latter is unseated from the lower valve seat in the 10 bottom of the case, said cap being provided with a central lengthwise opening and lateral branch openings —20— surrounded by deflecting plate —21— to allow the escape of the exhaust motive fluid from the 15 cylinder —5— into the receiving cup or tray —18—, from which it gravitates through a pipe —22— into an underlying drainage pan —23—, the latter having a pipe —24— leading from the bottom thereof to a sewer 20 or other suitable waste pipe, not shown.

The valve —17— is of considerably less cross sectional area than the chamber in the valve case —16—, in which it is located, so as to allow ample clearance for the escape 25 of the exhaust fluid from the cylinder —5— and is normally placed under the tension of a spring —25— which serves to lift it from its lower seat in the bottom of the case —16— and to close the passage in the 30 cap —19— when relieved from downward pressure in a manner presently described.

This valve is controlled by steam pressure from the boiler through the medium of a weighted lever —26— and a plunger —27—, 35 upon the upper end of which the lever rests, the lower end of the plunger being reduced in diameter to slide freely in a central opening in the cap —19— where it rests upon the upper end of the valve —17— to normally hold the latter closed against its lower seat, thereby normally cutting off communication between the main supply pipe —14— leading to one end of the cylinder —4— and the inlet —13— in the opposite 45 end of the cylinder —5—.

Secured to the main supporting frame or shelf —1— is a hollow steam-receiving shell —28— containing a diaphragm —29— which divides the chamber into lower and 50 upper compartments, the lower compartment being provided with a steam supply pipe —30— adapted to be connected to the boiler, not shown, but in which the steam pressure is to be regulated by the automatic 55 regulation of one or more of its dampers as —a—, shown diagrammatically in Fig. 1.

The diaphragm —29— is provided with a stem —31— extending upwardly through the upper wall of the shell —28— and is provided at its upper end with a hardened knife edge bearing against the lower edge of the adjacent lever —26—.

The adjacent end of the lever —26— is provided with hardened knife-edge bearings 65 —32— fulcrumed in upwardly extending

lugs —33— which rise from the upper wall of the shell —28— at one side of the diaphragm stem or plunger —31—.

This lever extends lengthwise of and above the upper face of the main supporting frame —1— and carries suitable weights —W— and —W'—, one of which, as the weight —W'— is adjustable lengthwise of and upon the lever to permit a closer regulation of the movement of said lever under 70 a predetermined boiler pressure in the diaphragm case —28— against the under side of the diaphragm —29— tending to lift the weighted end of said lever.

A pair of wheels —34— is journaled upon 80 the main supporting frame —1— and project into a cut-out in the upper side of the hollow rod —8—, preferably in vertical alignment with the intervening space between the ends of the cylinders —4— and 85 —5—, said wheels being provided with peripheral annular grooves —35— for receiving damper-operating cables or chains —36— which are passed around the opposite sides of the wheels and in opposite directions from the lower side thereof along the center of the cut-out in the hollow rod —8— and have their ends provided with hooks for engagement with anchor bolts —37— in opposite ends of the connecting rod 90 or tube —8—, said cable being passed over idlers —38— and around a suitable wheel —39— on one end of the damper shaft, as —40—, so that when the pistons —6— and —7— are moved in one direction or from 100 their normal positions, the damper —a— will be shifted from its normal open position to its closed position through the medium of the cables —36—, while the return of the pistons to their normal positions will 105 impart a corresponding positive return of the damper to its open position through the same medium.

The cylinders —4— and —5— are of such length as to allow sufficient movement of 110 their respective pistons to shift the damper from one extreme position to the other, but together with their respective pistons are of unequal area,—that is, the cylinder —5— and its piston —7— is of considerably 115 greater cross sectional area than, in this instance twice, that of the other cylinder —4— and its corresponding piston —6—, the purpose of which is to cause the piston —7— to be moved from its normal position, as shown in Fig. 1, to its other extreme position against the same pressure per unit of area acting in the opposite direction upon the piston —6—, thereby permitting both 120 pistons to be operated with practically the same hydraulic power.

In operation, assuming that the parts are in their normal positions shown in Fig. 1, and that the motive fluid is acting under full pressure on the smaller piston —6— and 130

that the weighted lever —26— is set so as to resist a predetermined steam pressure of, say, eighty pounds per square inch on the diaphragm —29—. Then, if the boiler pressure, as transmitted to the diaphragm —29— is below such predetermined degree, the valve —17— will be closed against its lower seat by the lever —26—, thus cutting off communication between the main supply pipe —14— and inlet —13— of the cylinder —5—, thereby allowing the main line pressure in the cylinder —4— to hold both pistons in their extreme inward or normal positions for opening the damper and keeping it open until the boiler pressure exceeds the predetermined degree referred to.

Now, if the boiler pressure acting upon the diaphragm —29— exceeds said predetermined pressure, it will flex the diaphragm upwardly, thereby producing a corresponding upward movement of the lever —26— about the fulcrum —32— against the action of the weights —W— and —W'— and releasing the pressure of the lever upon the valve —17— so that the spring —25—, aided by the water pressure in the branch section of the pipe —15— at the right of the valve, will lift the valve from its lower seat and thereby open communication through the branch pipe from the main supply pipe —14— to the inlet —13—.

It is now clear that the same pressure per square inch is acting in opposite directions upon both pistons —6— and —7—, but owing to the fact that the piston —7— is of considerably greater area than that of the piston —6—, the pressure acting thereon will cause both pistons to be moved from their normal positions toward the opposite ends of their respective cylinders, which movement, in turn, will be transmitted to the damper —a— through the medium of the cable —36— and its connection with the rod —8— to close said damper and to hold it closed until the boiler pressure in the diaphragm shell —28— is less than the predetermined degree referred to, whereupon the weights on the lever —26— will restore the latter to its normal position to close the valve —17— against its lower seat for cutting off communication between the main passage 14 and inlet —13— of the cylinder —5—.

When the valve —17— is closed in the manner just described, communication is still maintained between the inlet —13— and valve chamber of the case —16— through the medium of the corresponding section of the branch pipe —15—, thereby placing the adjacent end of the cylinder —5— in direct communication with the exhaust ports —20—.

Now, with the high pressure fluid to the piston —7— cut off and the inlet —13— connected with the exhaust ports —20— in

the manner just described, it is evident that the high pressure fluid acting upon the smaller piston —6— will restore both pistons and damper to their normal positions, and that the fluid in advance of the larger piston —7— will be forced out through the adjacent section of the branch pipe —15— and exhaust ports —20— into the receiver —18—, from which it escapes through the pipe —22— to the drainage pan —23— and thence to the waste pipe, not shown, through the drainage outlet —24—.

These operations are repeated as often as the diaphragm pressure in the valve case fluctuates above or below the predetermined degree at which the weighted lever —26— is set.

It is, of course, obvious that when downward pressure upon the valve —17— is released to open communication between the main supply pipe and cylinder —5—, said valve will be closed against the upper seat to cut off communication between said cylinder and the exhaust ports, the movement of the valve being limited to a very small degree, just sufficient to open either port at the opposite ends thereof when closing the other port, such movement being regulated by the adjustment of the screw cap —19—.

Although I have shown and described this device as applied to the operation of a draft damper, it is evident that it may be used for positively opening or closing any other kind of a valve which may be capable of regulating steam pressure of a boiler, or that of any other fluid-pressure-producing device without departing from the spirit of this invention.

What I claim is:

1. In a damper regulator, the combination of a pair of hydraulic motors having rigidly connected coaxial pistons of unequal diameter for operating the damper, means for supplying fluid under pressure to one end of the smaller motor, a by-pass leading from the supply pipe around said motors to the opposite end of the larger motor and including therein a valve case having a self-opening valve controlling the flow of the fluid under pressure through the by-pass, weight-operated means for closing the valve, and steam-pressure operated means for operating the first-named means against the action of its weight to release and permit the opening of the valve.

2. In a damper regulator, the combination of a pair of hydraulic motors having rigidly connected coaxial pistons of unequal diameter for operating the damper, means for supplying fluid under pressure to one end of the smaller motor, a by-pass leading from the supply pipe around said motors to the opposite end of the larger motor and including therein a valve case having a self-opening valve controlling the flow

- of the fluid under pressure through the by-pass, weight-operating means for closing the valve, and steam-pressure operated means for operating the first-named means against 5 the action of its weight to release and permit the opening of the valve, said valve case having an exhaust port and a secondary valve controlling the same, said secondary valve being closed by the opening of 10 the first-named valve and opened by said weight-operated means, the portion of the by-pass leading from the valve to the larger motor being in open communication with the exhaust port when the first-named valve is closed.
- 15 3. In a damper regulator for steam boilers, a pair of opposed piston motors having their pistons of unequal area and connected for simultaneous action by means of a piston rod having a cut-out in one side, grooved 20 pulleys extending into said cut-out and adjusted to work in opposite directions, means for supplying a motive fluid under pressure to both motors for operating the pistons, means for transmitting motion from the pis- 25 tons to the damper, and means controlled by steam pressure from the boiler for cutting off the supply to the larger motor when said pressure is at or below a certain degree and for admitting said supply when the 30 pressure is above said degree.
4. In a damper regulator for steam boilers, a pair of opposed piston motors having their pistons of unequal area and connected for simultaneous action by means of a hollow piston rod having a lengthwise cut-out 35 in one side, a pair of grooved pulleys projecting into said cut-out near the longitudinal center of the hollow rod and adjusted to work in opposite directions, a damper having a wheel thereon, cables attached to 40 said wheel and extending through the cut-out around the under side of the grooved pulleys, idlers for supporting the intermediate portions of the cable, means for supplying a motive fluid under pressure for 45 both motors for operating the piston, and means controlled by steam pressure from the boiler for cutting off the supply from the larger motor when said pressure is at or below a certain degree and for admitting 50 said supply when the pressure is above said degree.

In witness whereof I have hereunto set my hand this 25th day of January, 1917.

WILLARD A. KITTS, Jr.
